UNITED STATES PATENT OFFICE.

JOHN H. PHILLIPS, OF CHICAGO, ILLINOIS.

EXPANSION SHELL.

Original application filed July 21, 1919, Serial No. 312,243. Patent No. 1,379,210, dated May 24, 1921.
 Divided and this application filed February 19, 1921. Serial No. 446,378.

To all whom it may concern:

Be it known that I, JOHN H. PHILLIPS, a citizen of the United States, residing at Chicago, in the county of Cook and State of Illinois, have invented certain new and useful Improvements in Expansion Shells (Case A), of which the following is a description.

This application is a divisional case of my application Serial Number 312,243, filed July 21, 1919, now Patent Number 1,379,210 granted May 24, 1921.

My invention belongs to that general class of devices known as expansion shells, and relates particularly to a shell which may be employed to drill its own hole in concrete, brick, stone or like material, and then be utilized for fastening and holding various devices or mechanisms to said drilled material. Among the various uses to which expansion shells are put may be mentioned the supporting of pipe and wire systems and electrical, mechanical and other equipment, etc., from walls, ceiling and floors of concrete, brick, stone or like material.

My invention has among its objects the production of an expansion shell of the kind described that is simple, convenient, efficient, reliable, durable and inexpensive, and suitable for use wherever found applicable. It has particularly among its further objects the production of an expanding shell which may be placed in a suitable chuck of a percussion or rotary type of drill tool, and employed to drill the hole in which the shell is placed, the chuck then being removed and the shell then expanded so that it is securely and firmly, and to all intents and purposes permanently retained in place for the purpose of carrying such devices or equipment as may be found desirable.

It has particularly as an object of invention, the production of a shell which being employed as described to drill the hole in which it is to be seated, insures the securing of a hole of the right size and depth into which the shell will fit perfectly and in a most workmanlike manner.

Another object of my invention is to provide an expansion shell of the above described characteristics having a longitudinal split at one end thereof, said shell being adapted to be used in combination with a wedge-shaped expanding member insertable into said split to spread the shell at the split

end, said expanding means being adjustable to vary the degree of shell expansion.

Another object of this invention is to produce an expansion shell, as described, in which the expanding or wedging pressure is at the bottom of the hole and which when being permanently inserted in the hole which it drills, cuts its way to a seat against the walls of said hole, and is wedged tight and held securely in place while permanent load is attached.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a sectional view of my improved shell;

Fig. 2 is a similar view of the sections separated, with a bolt and expander shown;

Fig. 3 is a sectional view taken substantially through line 3—3 of Fig. 2;

Fig. 4 is a view in elevation of a modified form of bolt with an expander formed thereon;

Fig. 5 is a side view of the same;

Fig. 6 is a sectional view of the same taken substantially on line 6—6 of Fig. 4; and

Figs. 7, 8 and 9 illustrate a modified form of expander which may be detachably secured on a bolt similar to the securement of the expander shell in Fig. 2.

In the embodiment of my invention as disclosed in the drawings, I have shown a tubular shell which may be of one or more or the desired number of parts, as shown, there being two parts 1 and 2, which are arranged circumferentially to form the tubular shell, said parts being preferably provided with a cutting edge or teeth 3 at one end thereof. The parts are made of any suitable material in the preferred way, and of the desired size.

The end 5—5 opposite the cutting edge is preferably tapered to engage in a suitable chuck, and there may be holes or notches 6 in the walls of the shell parts into which a

suitable tool may be inserted to assist in releasing the same from the chuck, as well as to provide means for attaching a cooperating part. The opposed parts are preferably cut away at their toothed ends, as at 7, so as to form a tapered or V-shaped longitudinally extending recess thereat, and the walls 7' of said recess may be divergently inclined or beveled relative to each other 10 from their outer to their inner peripheries, as more fully described hereafter.

After using parts 1 and 2 of the shell to drill its own hole, said parts are then used with an expanding member as an expansion 15 or anchor shell in the hole so drilled, the useful drilling life of said parts being such that each shell will make its own hole.

A round hanger bar or bolt 15 is insertable through the bore of the shell, said bolt 20 being threaded at 16, and threadedly mounted on said bolt is a nut 17, the lateral wings 18 of said nut projecting beyond the end thereof and having tapered sides 20 and an outer edge 19 parallel to the axis of said nut.

It will be seen that when the assembled shell and nut 17 are inserted in the neat fitting hole, which said shell has drilled, the ends of wings 18 will come in contact with the bottom of the hole ahead of the shell 30 parts 1 and 2, and that any further travel of the shell in contact with the wedge-shaped wings 18 will cause parts 1 and 2 to spread or wedge against the walls of the hole. The wings 18 are of such width that 35 it will be necessary to force the shell parts to the bottom of the hole by driving. A few blows on the end 5 of the shell will drive it against the bottom of the hole, at the same time causing the cutting points or high 40 points on the outer surface of the shell to cut and imbed in the walls of the hole, thus seating and wedging it with a full bearing. The shell being tightly wedged or expanded 45 at the bottom of the hole before the permanent load or pull is applied to the rod or bolt 15, will insure that any spreading or wedging action due to such load or pull will be at the bottom of the hole.

In Figs. 4, 5 and 6, I have shown a bolt 21 50 having an integral wedge integral at one end thereof, said bolt being threaded at 22. The wedge wings shown have outer sides or faces 23 parallel to the bolt axis, and also have a pair of downwardly convergent, 55 inclined or tapered sides 24, the wings at the meeting edges of the tapered sides 24 and the vertical outer side 23 being beveled at 25, said bevel extending laterally of said meeting edges for their entire length. The 60 beveled faces 25 are preferably of a similar taper to the taper of the beveled faces 7' of the shell recess, so that when the wedge is moved axially of the shell parts after it has been inserted into said recess, it will fit snugly 65 therein and expand the shell parts. An-

other advantage of said double-toothed snug fit is that when the wedge is expanding, it will tend to force any dirt or other foreign matter between the shell edges into the interior of the shell.

Figs. 7 to 9 inclusive illustrate another form of wedge member 26, similar in shape to the wedge member shown in Figs. 4 to 6, the difference lying in the fact that the wedge 26 is a separate or detachable member like the wedge-shaped nut 17 illustrated in Figs. 1 to 3, and said nut 26 being also threaded at 27.

It will be obvious that the various features of the bolt and wedge-shaped expander wings combined in the several modifications may be combined as desired. I have not considered it necessary to illustrate the chuck by means of which the device is seated, said chuck being described in my co-pending application Serial No. 361,906, filed February 7, 1920. It will be noted that the device is substantially a self-drilling expansion shell which is especially applicable for fastening various devices to concrete ceilings and the like, requiring the use of round and flat hangers, wire ties, bolt and screw connections, etc. In using the device the shell is placed in the chuck and held firmly against the material to be drilled. The cutting edges or teeth may be brought to different points in the work by a slight back and forth rotary motion while the hammer or tool is operating. Thus, owing to the position of the cutting edges after drilling, the slight rotary movement is more desirable in the case of the larger sizes, where the pitch of the teeth is greater. In the smaller size having finer pitch, the jump or vibration from the blow of the hammer is sufficient to break off the material between the cutting edges, permitting the shell to be driven straight in under repeated blows of the hammer.

As the work progresses, the center or core corresponding to the bore of the shell breaks off into short pieces, and together with the cuttings falls down through the shell and out of the chuck. After the hole has been drilled to the desired depth, the chuck and shell are removed, the tapered expander mechanism and bolt or rod are then inserted through the bore of the plug and the shell and parts reinserted into the drill hole. The tapered expander is then operated to expand the shell parts, causing the same to be firmly and securely locked in place in the hole, and thereby locking the bolt or fixture fastener in place. To all intents and purposes, the same becomes substantially a permanent part of the wall, ceiling or the like to which the various devices or other equipment may be secured by means of said bolt or rod, or the equivalent. The device has many advantages in that it is not necessary to pro-

vide extra drills, as each shell may be employed to drill its own hole. The shells may be manufactured at comparatively small expense, and if desired, may be used 5 only one time, having sufficient life as a drill to serve the purpose. They may be constructed in any suitable manner, or any number of parts as described, and after forming, may be case-hardened or otherwise 10 treated so as to increase their durability. Among the decided advantages of the self-drilling expansion shells over the non-drilling shells is the perfect fit of the shell in its own hole, thereby requiring less 15 expansion and permitting more acute taper of the wedging member and a corresponding more powerful expansion than is possible with cast shells requiring greater expansion in order to accommodate the various variations 20 in the size of the holes resulting from the use of separate drills.

Having thus described my invention, it is obvious that various immaterial modifications may be made in the same without departing 25 from the spirit of my invention; hence I do not wish to be understood as limiting myself to the exact form, construction, arrangement and combination of parts herein shown and described or uses mentioned. 30

What I claim as new and desire to secure by Letters Patent is:

1. An expansion shell of the kind described comprising a tubular body split longitudinally and having wedge-shaped recesses formed at the opposed edges of said split at one end thereof, the sides of said recesses being convergently tapered from the inner to the outer periphery, and cooperating means 40 having wedge-shaped sides and bevelled rearwardly of the outer edges thereof and insertable into said recesses so as to bear against the faces of the side walls thereof and expand said shell.
2. An expansion shell of the kind described comprising a plurality of parts having wedge-shaped recesses therebetween at one end of the opposed edges, the side walls of each of said recesses diverging inwardly 50 from the outer periphery, and cooperating means arranged within said shell and extending laterally thereof, the outer faces of said means extending parallel to the shell axis and having side walls divergently bevelled from their outer to their inner edges, 55

said means being insertible into each of said recesses so as to bear against the faces of the side walls thereof and expand the shell at each line of juncture.

3. An expansion shell of the kind described comprising a tubular body having a wedged-shaped recess at one end thereof, the sides of said recess being convergently tapered from the inner to the outer periphery of the shell, and cooperating means comprising a member having wedge-shaped sides insertable into said shell to bear evenly against the faces of said recess to expand said shell and being of a greater length than said recess so as to extend beyond the end of said shell and be engageable with the bottom wall of the hole in which said shell is inserted. 60 65 70

4. An expansion shell of the kind described comprising a plurality of parts having wedge-shaped recesses therebetween at one end of their opposed edges, the side walls of each of said recesses diverging inwardly from the outer periphery, and cooperating means arranged within said shell and extending laterally thereof, the outer faces of said means extending parallel to the shell axis and having side walls divergently bevelled from their outer to their inner edges, and convergently tapered from their tops to 80 85 their bottoms, said means being insertable into each of said recesses so as to bear against the faces of the side walls thereof and expand the shell at each line of juncture. 75

5. An expansion shell of the kind described comprising a tubular body having a wedged-shaped recess at one end thereof, the sides of said recess being convergently tapered from the inner to the outer periphery of the shell and cooperating means comprising a member having wedge-shaped sides and bevelled rearwardly of the outer edge of said sides so as to bear evenly against the faces of said recess to expand said shell, said member being of greater length than said recess so as to extend beyond the end of said shell and be engageable with the bottom wall of the hole in which said shell is inserted. 90 95 100

In testimony whereof, I have hereunto signed my name in the presence of two subscribing witnesses. 105
